UNITED STATES PATENT OFFICE.

ABRAHAM B. LANDIS, OF WAYNESBOROUGH, PENNSYLVANIA.

GRINDING-MACHINE.

SPECIFICATION forming part of Letters Patent No. 425,230, dated April 8, 1890.

Application filed January 8, 1890. Serial No. 336,239. (No model.)

To all whom it may concern:

Be it known that I, ABRAHAM B. LANDIS, a citizen of the United States, residing at Waynesborough, in the county of Franklin, State of Pennsylvania, have invented certain new and useful Improvements in Grinding-Machines, of which the following is a specification, reference being had therein to the accompanying drawings.

10 My invention relates to universal grinding-machines, adapted to do a great variety of work, as straight and tapering, either inside or outside; and my invention consists in the arrangement of the parts by which the relative positions of the table, the head-block, and the grinding-wheel can be adjusted, and in the means for retaining the spindle-head block connected with the table between the head-stock and foot-stock, as will be herein-
15 after described, and pointed out in the claims, some of the features being more fully described in a companion application, bearing Serial No. 311,681, filed May 22, 1889.

In the accompanying drawings, Figure 1 is a top view of a grinding-machine constructed in accordance with my invention. Fig. 2 is a top view of the supporting-plate for adjustably carrying a spindled head on the side of the machine opposite the grinding-wheel. Fig. 3 is a side view of the spindled head and its supporting-plate with a portion of the supporting-table in section, and Fig. 4 is a front view of the same. Fig. 5 is a top view of a portion of the machine, showing its application to grinding inside tapering work. Fig. 6 is a top view of a portion of the machine, showing its application to grinding outside tapering work.

The machine consists of a base having a bed mounted thereon, in which are located all the feed or traverse gearing. On top of this bed is located a plate C, and on this table is pivoted a table D, which can be swung horizontally around the central bolt d^5 and is secured in position by bolts d^7 , passing through curved slots in the ends thereof and adjusted accurately by degrees and fractions thereof (indicated at d^8) by means of the screw d^4 , which is pivoted in a bearing 2 and the hand-wheel d^2 . Upon this pivoted table are mounted the head and foot stocks, having center pins to revolve the work upon, the head-stock

E having a fixed position, while the head-block f^4 is adjustable. The foot-stock is made to overhang a pan I the entire length of its adjustment, so that the water which drops off the shaft that is being ground will drop into this pan and run off at the spout i , located at the center of its length so that it will run into the channel c^2 , whatever may be the position of the pivoted table, and thence through the hole c^3 .

The head-block f is secured to the table D by bolts d^3 , set at an angle, which brings said head-block firmly against the long shoulder d^9 on said table. For angular grinding, when it is desired to move the table D to an extreme position, as shown by dotted lines in Fig. 1, and to secure it in that position the bolt d^7 is removed from its seat and inserted in one of the holes c^4 for either extreme, and the screw d^4 and its bearing 2 are removed from the machine to give a wide range of angle for taper work.

The grinding-wheel A is carried by a frame F, which is adapted to be swung around upon its pivot-bolt to properly locate the wheel for the work.

To grind face-work in a chuck, either straight or at an angle, a supporting-plate f is used. Said plate is mounted on the table D in the center of its length opposite the pivotal point, and is secured in precisely the same manner as the foot-stock, only with two screws and a tongue f^2 entering a groove f^9 in the table D, the purpose of said tongue being to retain the plate f centrally opposite the pivotal point d^5 of the table. The top of the supporting-plate f has three radial grooves f^3 , in either one of which the spindled head-block f^4 can be secured, having a tongue f^6 to engage with the groove f^3 , and is retained by the inclined bolt f^5 . In Fig. 1 the supporting-plate f is shown at right angle to the table D. Angular positions can now be obtained for any angular work by means of the large protractor-scale d^8 , and said positions are carried to its limit. For more acute angles the spindled head f^4 is transformed to one of the side slots f^3 .

The advantage obtained by the means above described are that a large protractor-scale can be used for this angular grinding, and thus fractions of degrees can be used and

greater accuracy be obtained, and for face-grinding the automatic traverse can be used and also a comparatively large emery-wheel, the object operated upon being thrown forward to about the pivotal point of the table D, as shown; and further, the advantage of this position for face-grinding is that it brings the work directly over the water and grindings receiving pan I, and avoids the ordinary 5 slop of water over the finished portions and sides of the machine. To help attaining these results the pulley f^7 for driving the chuck f^8 is placed immediately behind said chuck, and said pulley is thus brought in correct align- 10

ment with the shaft above the same, as for 15 straight grinding.

Having now fully described my invention, I claim—

In a grinding-machine, the combination of a pivoted table D, with a spindled head and its supporting-table f, having a series of radial grooves f^3 , substantially as described.

In testimony whereof I affix my signature in presence of two witnesses.

ABRAHAM B. LANDIS.
